United States Patent Office.

JAMES LAWTON, OF GLENHAM, NEW YORK.

Letters Patent No. 95,237, dated September 28, 1869.

IMPROVEMENT IN FEEDING-ATTACHMENT FOR CARDING-ENGINE.

The Schedule referred to in these Letters Patent and making part of the same.

To all whom it may concern:

Be it known that I, JAMES LAWTON, of Glenham, in the county of Dutchess, and State of New York, have invented a new and improved Feed-Attachment to Carding-Machines; and I do hereby declare that the following is a full, clear, and exact description thereof, which will enable others skilled in the art to make and use the same, reference being had to the accompanying drawings, forming part of this specification, in which—

Figure 1 represents a side view of my improved feed-attachment to carding-machines.

Figure 2 is a vertical transverse section of the same. Similar letters of reference indicate corresponding parts.

This invention relates to a new attachment to carding-machines, which is to be a substitute for the ordinary strap heretofore in use.

This strap, which is provided with projecting prongs, and which has for its object to guide and carry forward the material on the main feed-belt, is unreliable for the two following reasons: In the first place, it is apt to slip on the rollers, and thereby fail to effect its purpose; and in the next place, it is liable to break and to be carried between the feed-rollers, where it makes so much confusion that it is very troublesome to be removed and replaced.

The present invention consists in the employment of rollers in place of the strap, said rollers having teeth, to carry the material on the feed-belt. They are geared together with the feed-roller, so that they must remain in operation as long as said rollers are in action.

A, in the drawing, represents the feed-belt of the ordinary carding-machine.

B B are the feed-rollers of the same.

In front of the feed-rollers, and above the ends of the feed-belt, in the frame C, are hung three, or more or less, rollers, D D, which have projecting prongs, a a, on their edges, and which are all hung on the same level.

These rollers carry toothed wheels, b b, on their axles, said wheels being connected by pinions, c c, with each other and with the feed-rollers, so that the rollers D are all turned in the same direction, as indicated by the arrows in fig. 1.

A sheet-metal or other shield, E, is interposed between the gear-wheels and the feed-belt, to prevent the material from coming in contact with the gearing.

The rollers cannot get out of order, and cannot slip, so that they will be sure to operate satisfactorily.

Having thus described my invention,

I claim as new, and desire to secure by Letters Patent—

As an improvement upon the Apperly and Clissola feed for carding-machines, the combination of the pronged rollers D, arranged on the same level, the toothed wheels b b, pinions c c, and shield E, all operating to move the roving to the card-cylinder, as and for the purpose specified.

JAMES LAWTON.
